MACHINE FOR FILLING AND SEALING
PAPER BAGS

Harold G. Eynon, Philadelphia, Pa.

Application May 6, 1930, Serial No. 450,103

55 Claims. (Cl. 226—51)

My invention relates to mechanism for filling paper bags, with more particular reference to mechanism for picking up the bags, opening them, holding them for the filling and closing operations, and then discharging the filled and closed bags, the invention being thought to have its widest application in automatic bag filling machines.

A purpose of my invention is to provide mechanism of the character indicated that is easy and inexpensive to manufacture and well adapted to the needs of service.

I present the paper bags to my mechanism folded flat, presenting one side of the bag up and the bottom of the bag down.

A further purpose is to pick up a flat bag by means of a movable suction member, applying the suction surface of the member to an upwardly directed side of the bag.

A further purpose is to effect a resilient seal between a surface of a bag and a suction member.

A further purpose is to open a folded bag by applying one suction plate to the side and another suction plate to the bottom of the bag and angularly moving one of the plates with respect to the other.

A further purpose is to hold a paper bag open for filling and closing operations by suction plates applied respectively to the bottom of the bag and to an adjacent side thereof.

A further purpose is to move a filled bag from a filling station to a discharge position by means of a movable suction plate, dropping the bag to discharge by releasing the suction.

A further purpose is to pick up a bag by a suction member applied to one side thereof and to use this plate without releasing its initial hold for successively opening the bag, for holding it throughout the operations incident to bag filling and closing and then for bag discharge, effecting discharge by moving the plate so that its suction surface and depending bag are above the point of discharge and then dropping the bag to discharge by releasing the suction.

A further purpose is to use cooperating suction plates for picking up, opening, holding and discharging bags, making one of the plates movable and the other stationary, applying the movable plate to one side of a folded bag, moving the plate to apply the bottom of the bag to the stationary plate and then while the plates are respectively holding one side and the bottom of the bag turning the movable plate with respect to the stationary plate in order to open the bag.

A further purpose is to apply suction to a movable suction plate through a valve opened by the plate and a cooperating stop as the plate moves to pick up a bag.

A further purpose is to provide a desirable orbit of movement for a movable suction plate,

keeping the plate angularly elevated during its outward movement toward a folded bag then turning the plate downward upon an upwardly directed side of the bag, then giving the plate a rectilinear return movement until the bottom of the bag has been brought to a stationary suction plate, then turning the first suction plate upwardly to open the bag.

A further purpose is to provide a desirable form of valve mechanism for determining the opening and closure of suction to movable and stationary suction plates that are adapted to co-operate in picking up, presenting, opening, holding and discharging bags.

A further purpose is to turn suction into a movable suction member as it moves to picking position by the engagement of a valve opening member with a suitable stop and to turn it off by a corresponding engagement between a shutoff member and another stop as the member moves into discharging position.

A further purpose is to use a pneumatic cylinder and piston mechanism pivoted upon a transverse axis to effect the variant positioning of a movable suction plate in order to adapt the plate to pick up a flat paper bag, to present the picked bag with its bottom in registry with a stationary suction plate and to open the bag by cooperative action of the two plates.

A further purpose is to admit the air suction to suction plates respectively carried upon the arms of a turn table through the said supporting arms.

A further purpose is to provide each one of a plurality of arms of a turntable with bag picking and holding mechanism that is adapted to receive jarring for settling the contents of a filled bag without transmitting the jarring movement to any material extent to the body of the machine.

A further purpose is to provide a desirable form of automatically engaging and releasing clutch between a positioning part of a suction member mounted on the head of a turntable and the outer end of an operating piston rod not turning with the table, and that is adapted to move the suction member through an operating cycle when in clutch connection with the said part, and to operate successively upon the suction members of successive heads spaced around the turntable as they are successively in position at the said piston rod.

A further purpose is to mount a piston and cylinder member at the receiving position and a similar member at the discharge position of an intermittent turntable for filling paper bags, providing clutch connection between a positioning part of a movable member for picking up, presenting and opening the bag and the ends of the piston rods adapted to automatically connect when the heads successively come to rest.

at the piston and cylinder members and to automatically release as the turntable moves on.

A further purpose is to operatively connect a movable bag-picking, bag-presenting and bag-holding member with the piston rod of a transversely pivoted pneumatic cylinder to effect an arcuate movement of the cylinder member during a forward stroke of the piston and to use this arcuate movement to reverse the piston, thereby adapting the piston to reciprocate once back and forth along the cylinder each time the air is applied to the cylinder, in order to move the picking, presenting and holding member throughout its cycle each time the air is applied to the cylinder.

Further purposes will appear in the specification and in the claims.

I have elected to show one only of the many forms of my invention, selecting a form that is practical and efficient in operation and which well illustrates the principles involved.

Figures 1, 2 and 3 are diagrammatic views illustrating broadly my method of picking up the bag, presenting it, opening it and holding it for the filling operations.

Figure 4 is a diagrammatic view illustrating a turntable to which my invention is well adapted to be applied.

Figure 5 is a side elevation of a portion of the turntable shown diagrammatically in Figure 4, showing one of five similar head-and-arm units spaced around the table and that come to rest successively at the positions 1 to 5 of Figure 4, the view showing one of the head-and-arm units at number 1 position of Figure 4, which is the position for picking up, presenting and opening the successive bags.

Figure 6 is a sectional top plan of Figure 5, the section being taken on the line 6—6 of Figure 5.

Figure 7 is an enlarged side elevation of a portion of Figure 5, modified however in a minor detail.

Figure 7a is a fragmentary vertical central section of one of the valve mechanisms seen in elevation in Figure 7, certain structure being broken away.

Figure 7b is a section taken on the line 7b—7b of Figure 7a.

Figure 8 is a sectional elevation of Figure 7, showing the travelling vacuum plate in the picking position.

Figure 9 is a top plan view of Figure 8.

Figure 9a is a detail of Figure 9.

Figure 10 is a sectional plan view of the structure of Figure 9.

Figure 10a is a fragmentary partially sectioned view corresponding to a portion of Figure 10 but illustrating a detail of the structure shown in Figures 5 and 6, not used in the form of Figures 7 to 10.

Figure 11 is an enlarged side elevation of part of Figure 5, comprising mechanism that does not rotate with the turntable.

Figure 12 is a section along the line 12—12 of Figure 11, with the cylinder however turned transversely to its supporting tubular fork and the view illustrating the supporting and feeding means for the structure of Figure 11.

Figure 13 is a section of Figure 12 on the line 13—13.

Figure 14 is an end elevation of Figure 13 showing valve resetting mechanism.

Figure 15 is a fragmentary bottom elevation,

part section, corresponding to a portion of Figure 13 but with the valve mechanism in reverse position from that of Figure 13.

Figures 16 to 21 inclusive are views showing the orbits of characteristic points of mechanism embodying a desirable form of an important portion of my invention.

Figure 22 is a plan view showing a desirable form of face for the movable suction member.

Figure 23 is a section taken upon the line 23—23 of Figure 22.

Figure 24 is a plan view of a desirable form of face for my fixed suction member.

Figure 25 is a section taken upon the line 25—25 of Figure 24.

Like numerals refer to like parts in all figures.

Describing in illustration and not in limitation and referring to the drawings:—

It is believed that the present invention will find its widest application with automatic machines for filling paper bags, to be applied upon the duplicate heads of an intermittent turntable, each head of the turntable successively picking up a bag, presenting it, opening it and holding it for filling, jarring, closing and final discharge, the heads operating one after the other through the same cycle of operations upon successive bags, the mechanisms for carrying out different phases of the cycle being placed adjacent the different rest positions of the heads.

Nevertheless the invention is of wider application, being well adapted to use elsewhere than on turntables, and I have therefore so illustrated it in Figures 1 to 3, where I omit parts special to turntable structure and endeavor to indicate broadly my method of picking up a bag, of presenting it, of opening it, of holding it for operations incident to filling and closing, and of discharging the filled and closed bag.

Referring to Figures 1 to 3, I use movable and stationary suction boxes 25 and 26 and a bag supporting tongue 27, a flat bag 28 being supported on the tongue with one side 29 up and the bottom 30 of the bag down.

I move the box 25 from an elevated position, as shown in Figure 1, along the path indicated by the arrows, to the dot-and-dash position of Figure 1, thereby applying its suction face 31 to the upwardly directed side 29 of the bag, securing firm suction connection between the side 29 of the bag and the face 31 of the suction box.

Desirably the suction face 31 engages the full width of the side 29 of the bag from its normally bottom edge 32 upwardly along the side as far as is consistent with non-interference with closing operations.

From the position shown in dot-and-dash in Figure 1, I move the suction box 25 in the direction of the arrows of Figure 2 to the position shown in full line in Figure 2, the movement being preferably parallel to the plane of the flat bag until the bottom of the bag is over the suction face 34 of the stationary suction box 26. In this approximate position of the bag 28 is brought into engagement with the box 26. I prefer not to effect this engagement by the movement of the bag parallel to the face of the box 26 because I desire to use relative movement of the bag and the box 26 perpendicular to the suction face on the box as a means of turning on the suction.

I now turn the movable suction box 25 angularly upward about the edge 32 of the bag, as indicated by the arrows 35 of Figure 3, from its position shown in full line in Figure 2 and in

dot-and-dash at 36 in Figure 3, to the position shown in full line, Figure 3.

During this movement the bag 28 opens, as throughout the movement the bottom 30 is held against the upward face of the stationary box 26, while the side 29 of the bag has suction connection with the face 31 of the moving suction box 25, so that when the box 25 reaches the full line position shown in Figure 3, the bag is open.

10 The bag is now firmly held by the two suction plates 34 and 31, one at the bottom and one at the side, with the open bag in position for easy filling, jarring, closing and ultimate discharge.

The filling, jarring, and closing of the bag may 15 be accomplished in any suitable way, by hand or by mechanism, as desired.

In discharging the filled bag, I release the suction under the bottom of the bag and then 20 outwardly move the box 25 along the same path as indicated by the arrows of Figure 1 or the arrows 37 of Figure 3, the box 25 carrying the bag outwardly and dropping it as it reaches the position shown in dot-and-dash at 38, Figure 3, by releasing the suction back of the plate 31.

25 Discharge takes place without interference from the charging tongue member 27 which has been moved out of the way.

When applied to a turntable, the discharge position takes place at a different point from the 30 picking up, presenting and opening positions of the bag, and suitable discharge chutes may be provided to carry the filled bags to any desired receptacle.

Since the widest application of my invention 35 is believed to be upon the head-and-arm units of an intermittent turntable, and since that turntable mechanism in itself is well known and therefore irrelevant to the present invention, I show in Figure 4 what is intended for a conventional illustration of any turntable adapted to receive mechanism embodying my invention.

In this figure the central portion includes stationary and intermittently rotating structures 40 and 41 and five arms 42 extending outwardly 45 from the rotating structure and carrying heads 43 that have details embodying important features of my invention.

The head and arm units are uniformly spaced around the table, are desirably all alike, and at 50 successive periods of rest of the table successively occupy the positions 1 to 5 of Figure 4.

There is thus always one head at each rest position during each rest period of the table, successive phases of the bagging operations taking 55 place at the successive rest positions.

A head at position 1 picks up a bag, presents it, opens it and holds it throughout subsequent positions of the head until the bag has been filled, jarred and closed by operations taking place while 60 the head is at positions 2 and 4 and finally discharges the filled and closed bag when the head is in position 5.

Each head includes cooperating suction boxes 25 and 26 as in Figures 1 to 3, the movable box being moved through its cycle by a pneumatic engine 44 when picking up, presenting and opening the bag while the head is at position 1, and by a pneumatic engine 45 when discharging the filled bag while the head is in position 5.

70 The pneumatic engines 44 and 45 are suspended from the stationary structure 40 of the turntable, are alike, and each adapted to automatically connect and disconnect with mechanism on the head for moving the suction box 25 throughout its prescribed path of movement.

While the filling and jarring of the bag will in practice almost invariably be done by automatic mechanism, all of these operations may optionally be effected by hand.

Figures 5 and 6 are fragmentary elevation and 5 sectional plan views showing part of the turntable and one of the arm-and-head units, the other arm-and-head units being desirably the same as that shown in Figures 5 and 6 so that description of one arm and head may be considered to apply to all.

I provide the turntable with an interior suction chamber 46, to which I apply continuous suction, as by connecting it to suitable suction apparatus, and I make the arms 42 that extend to 15 the different heads hollow conduits for transmitting suction to the boxes 25 and 26 (Figures 5 and 8).

I vertically bore the outer end 47 of each arm through the hollow 48 thereof to receive 20 and fit a cylindrical hollow shank 49 of the head 43.

The head is thus carried by the shank 49, which is surrounded by the hollow interior of the arm and ported at 50 into the hollow of the arm, admitting into the interior of the shank continuous suction from the suction compartment 46 at the turntable.

The shank carries an outwardly directed flange 51 above and a threaded portion 52 below the 30 end of the arm, the head being clamped to place against the upper and lower heavy rubber washers 53 and 54 above and below the end of the arm by tightening a suitable nut 55 at the lower end of the shank (best seen in Figures 5, 7 and 8). 35

By means of the rubber washers 53 and 54 and rubber packing rings 56 (Figure 8), I very effectively insulate the heads from receiving undue vibration incident to the jarring of one of the heads at one of the rest positions during each 40 period of rest of the turntable, at the same time sealing the joint against leakage of air.

A plug 57 at the lower end of the shank member 49 provides a convenient point of application of jarring impacts which may be effected by 45 suitable jarring mechanism or by hand.

The purpose of the jarring is to cause a settling of the material charged into the bag, and one of the heads will always be under jarring during each rest period of the turntable. 50

The hollow shank 49 is shown as an integral portion of a two compartment box 58 (Figure 8), of which the hollow shank forms one compartment and the stationary suction chamber 26 (Figures 1 to 3 and 8) the other, the space inside the 55 hollow shank being always under suction, while the interior of the compartment 26 is alternately under suction or at atmospheric pressure according to the setting of a valve 59 inside the chamber 26 (Figures 8 and 10). 60

The compartments 26 and 49 have respectively lower and upper portions that are on opposite sides of a vertical wall 60 which is ported at the valve 59, and perpendicular to a radius of the turntable through the valve. 65

Preferably the stem 61 operates longitudinally in a direction substantially radial of the turntable axis, the valve member 59 being inside the compartment 26, with an inward position, that of Figures 8 and 10, at which it closes the port 62 to the compartment 49, leaving open a port 63 to atmosphere, and an outer position, that of Figure 7a, in which the stem and valve have been moved radially outward to close the port 63 to atmosphere and open the suction port 62. 75

The suction compartment 49 has side openings at 64 and 65 (Figures 7 to 10) into sets of intermediate hinged pipings 66 and 67 that connect into opposite sides of a compartment 68 back of 5 and integral with the movable suction compartment 25, with which it has valve connection at 69, Figures 8 and 10.

The sets of pipe connections between the movable and stationary suction compartments 49 and 10 68 have suitable hinge connections at 70 adapting the two-compartment box 71, which includes the compartments 25 and 68, to move along its desired path without interrupting the continuous suction applied to the chamber 68, or the continuous 15 suction in the chamber 25 except as such movement is used to open and close the valve 69 between the compartments 25 and 68.

Detail features of my invention include desirable forms of valve connections controlling the 20 holding suctions inside the compartments 25 and 26, whereby the suction is admitted to the compartment 25 as its suction face reaches picking position, admitted to the compartment 26 as the bottom of the bag is being presented to the plate 34 25 preparatory to opening the bag, released in the compartment 26 after the bag has been filled and closed preparatory to discharge of the filled and closed bag, and released in the compartment 25 to effect final discharge by dropping the bag from 30 the downwardly directed extended face 31.

The valve mechanism controlling the suction in the compartment 26 under the stationary suction plate is shown in Figures 5, 6, 7, 7a, 8 and 10.

As best seen in Figures 7a and 8, the horizontal 35 valve stem 61, extending radially of the turntable axis, carries inside the compartment 26 a fibervalve 59 which closes alternatively the radially spaced ports 62 and 63, respectively, to the compartment 49 and to atmosphere.

40 The stem is guided at 72 and 73, the outer guide comprising inner walls of the port 63 and a non-circular enlargement 74 of the stem.

The stem at its inner position presents the inner 45 side of the valve against the port 62 and in its outer position presents its outer side against the port 63, the plate 34 being in the two cases respectively without and with suction.

When in its inward position (Figure 8), the 50 compartment under the stationary suction plate is open to atmosphere and closed from the suction compartment 49, while when the valve stem is moved into its outer position (Figure 7a) the reverse is true, the atmospheric port being closed and the chamber being under suction through 55 the port 62 from the compartment 49.

In usual practice the compartment 26 under the suction plate 34 will be under continuous suction (Figure 7a) from the time the bottom of the bag is presented to the suction plate until the bag 60 is opened, filled, jarred and closed and is ready for discharge. The valve is then moved inward to the position shown in Figure 8, which instantly releases the suction under the plate and permits the bag to be readily moved away by the 65 upper suction plate, which at this time is still under suction.

The valve stem 61 is provided with longitudinally spaced inwardly and outwardly directed shoulders 75 and 76 (Figure 10) and outer and inner sliding sleeve 77 and 78 intermediate the shoulders.

The inner sleeve 78 carries laterally extending rods 79 and 80, Figure 10.

75 Swivel heads 81 at the outer ends of these rods are pivoted loosely at 82 to rocker members 83

(Figures 5, 7 and 10) and 84 (Figures 8 and 10) at opposite sides of the casing.

The rocker members 83 and 84 on each side are alike, each having a fixed pivot at 85, and a loose connection at 82 to the respective swivel 5 head 81. The upwardly extending arm 86 from each rocker (Figure 7) is pivotally secured to one the links 87 (Figures 5 to 9, which in turn is connected to a bell crank 88, best seen in Figure 7a. The bell crank 88 is in position to be engaged 10 and moved by the movable suction member as it moves to bag-presenting position.

The bell crank rockers 88 are alike, each being pivoted at 88', and having an arm 89 connected to the links 87 and an arm 89' extending at right 15 angles thereto (Figure 7a).

The inner arm 89' is in position to be engaged and deflected when the lower wheels 90 of the upper suction member 25 move to the position shown in Figure 7, the deflection of the arm 89' 20 moving the valve to close the compartment 26 to atmosphere and to open it to suction (Figures 5 and 7 to 10).

In Figure 8 the inner arm 89' of the rocker member is shown extending upwardly in position to be deflected downwardly when the wheel 90 of the upper suction member follows the depression 91 at the rear end of its guideway 92.

I provide means for maintaining the valve stem 61 spring pressed to position, whether this position is upon the port 62 or the port 63.

This mechanism for effecting resilient pressure tending to close the valve at whichever port the valve is seated includes (Figure 8) the slideable sleeve 77, upper and lower links 93 and 94 35 from top and bottom portions of the sleeve transverse and laterally projecting pins 95 and 96 respectively at the upper end of the link 93 and at the lower end of the link 94, pins 95 and 96 being adapted to slide in vertical guideways 97 and 98 40 for the projecting portions of the pins and strong tension springs 99 and 100 between the vertically spaced pin projections.

The pins press together in the horizontally spaced vertical guideways, tending to force the 45 vertically spaced ends of the links 93 and 94 together and thereby pressing the sleeve 78 outward or inward according to the slope of the links, which reverses at midposition of the sleeve.

The links and sleeve are given dimensions 50 adapting them to pass between the vertical guide members 97 and 98.

Thus, as seen in Figures 7, 7a and 7b, the links have passed their midposition and tend to hold the valve against the seat 63, while in Figure 8 the 55 links are on the opposite side of their midposition, and tend to press the valve toward the seat 62.

When the wheels 90 depress the member 89, the movement is transmitted through the links 87, 60 and the rockers 83 and 84, to the sleeve 78, moving the sleeve along the valve stem 61 against the retractive pressure of the sleeve 77 until the links 93 and 94 reach and pass the vertical sleeve 77, at which time the sleeve 77 snaps forward 65 and reverses the position of the valve by its engagement with the inward shoulder 75 of a knob 101 on the outer end of the valve stem.

The suction is turned off and the connection is open to atmosphere when the turntable moves 70 the head to position 5, Figure 4, across the wedge surface of a suitable stationary wedge member 102, which deflects the knob 101 radially inward to a point that reverses the slope of the links 93 and 94, the lower ends of these links and the sleeve 77 connected thereto. The sleeve 77 then 75

flies inward along the stem, engaging the outer arm of the sleeve 78, and pushing this sleeve against the shoulder 76, thereby pushing the valve stem inward until the valve engages and 5 closes the port 62, with the valve stem horizontally continuously pressing the valve home against the port 62 to maintain atmospheric pressure inside the compartment 26 under the stationary suction plate.

10 The valve mechanism between the compartments 68 and 25 of the movable suction box is best seen in Figures 5 to 10.

15 The valve 69 is mounted inside the compartment 25 upon a longitudinally movable stem 103 which is guided at 104 and 105 to alternatively close a port 106 into the compartment 68 or a port 107 to atmosphere. The valve, its ports, and the inner portion of the valve stem are all generally like the corresponding members of the 20 compartments 26 and 49 already described.

25 In Figure 10 the fiber valve members 69 are shown closing the port 107 to atmosphere but are adapted to move to the right to close the suction port 106 with an opening of the compartment 25 to atmosphere through the port 107.

The outer end of the valve stem 103 has connection at 108 with an operating member 109. The connection 108 is shown as a pivot connection, but except for purposes of manufacture the 30 operating member 109 might be integral with the stem 103.

35 The operating member is provided with a loose slot and pin connection 110 (Figure 9a) to one arm of a rocker 111, which is pivotally supported at 112 and has at its other end a loose slot and pin connection 113 with an auxiliary operating member 114.

40 The pins of the connections 110 and 113 may desirably comprise rigid portions of the rocker member, the slots at these connections in the members 109 and 114 respectively permitting an arcuate movement of the rocker to either side of a midposition transverse to the valve stem and to the operating members 109 and 114.

45 A spring 115 connected at one end to an outer end of the rocker arm, as to the pin at the connection 110, is anchored at its other end to the casing structure at a point 116 aligned with the pivot of the rocker member and the other end of the spring when the rocker is in its desired midposition, so that when the valve stem is positioned beyond its midposition it is spring pulled to move further away from its midposition.

50 The valve is thus spring pulled to closure when it is closing the port 107 to atmosphere and also spring pressed to closure when it is closing the port 106 to the suction compartment 68.

55 It will be seen that the operating members 109 and 114 move in and out in reverse directions, either moving in while the other is moving out, and vice versa, and that the valve may always be reversed by pushing inward on one of the operating members.

60 I preferably effect the reversals by the use of suitable stationary wedge members 117 (diagrammatically illustrated in Figure 4) of which one only has been shown (Figures 8, 9 and 10).

65 One of these reversing wedge surfaces engages and pushes the knob end of the member 114 as the movable suction box moves into picking position, and the other engages and pushes inward the knob end of the member 109 as the box moves into its discharge position.

70 There are thus two stationary wedge members,

one for each of the operating members 109 and 114. The first pushes the member 109 inward to effect discharge of the filled and closed bag at the fifth position of rest of the turntable (Figure 4) and the second pushes the member 114 inward at the picking position, which is the first position of the turntable.

75 These wedges may be exactly alike with the single exception that they are placed at different angular positions of the turntable to engage 10 different operating members, 109 and 114 respectively. Each pushes its member inwardly a distance sufficient to reverse the valve, in the one case to shut off a suction hold on the filled bag and in the other case to apply suction inside the 15 holding member in order to effect picking.

The two compartment movable suction box 71 is supported by upper and lower pairs of wheels 118 and 90 that roll on upper and lower tracks 119 and 92 of stationary vertical side pieces 120 20 and 121 that are similar and supported from the top of the two compartment stationary box 58.

25 The lower wheels 90 move back and forth along the spaced tracks or guideways 92 on the two side pieces, the path being straight and horizontal except for the depressions 91. The forward and retracting movements take place along the same path.

30 The upper wheels 118 move forward along one path, with the suction face 31 raised, and retract along another and lower path with the suction face directed downward in position to carry the picked bag rearward while holding it horizontal, so as to present the bottom of the folded bag 35 horizontally downward upon the horizontal stationary suction face 34.

35 The track or guideway for the upper wheels thus includes upper and lower portions, the upper track comprising gate members 122 which are pivoted at 123 and rest to the right of their 40 pivots (Figure 7) upon stationary webs 124 that form a portion of the lower guideway.

45 The right ends of the gate rails 122 are engaged underneath and lifted by the wheel 118 as the suction member 71 is moving to the position of Figure 5 in opening the bag, the ends of the rails latching back to such a position that the wheel 118 must travel on top of the rails when it next moves outward.

50 During its outward movement from the position shown in full line Figure 7, the suction member 71 moves forward with its face 31 vertical until the lower wheel 90 reaches the position 125 at the end of its forward travel, the upper wheels 118 during this movement rolling horizontally 55 along the rails 122 to the position 126.

55 After the lower wheels come to rest at 125 the member 71 swings outward to the left in an arc about the axis of the lower wheels to come ultimately to rest upon a folded bag on the tongue 27 with the front wheel in the position 127 resting upon a stationary return rail 128, any upward movement of the wheels 118 being prevented by a suitable guideway surface spaced above the rail 128, and illustrated as comprising surfaces 129, 130, and 131 respectively upon a movable latch member 132, upon an arm integral with the horizontal rail 122 and upon the under side of the web 124.

70 The path of the wheels 118 between the positions 126 and 127 is indicated by the dotted lines 133 and 134 (Figure 7), the members 122 and 132 being deflected by the wheels 118 respectively to the dot-and-dash positions 135 and 136 and drop- 75

ping back to the full line positions of Figure 7 when the wheels 118 reach the position 127.

During the return movement of the movable suction plate the suction face of the member 71 is horizontal, the wheels 118 rolling to the right along the rail 128, the guideway surfaces 129, 130 and 131 over the wheel insuring that the wheel travels back horizontally. The surface 131 guides the wheel downward into a depressed portion 137 of the track, the tracks of both wheels being correspondingly depressed at 137 and 91 for presentation of the bottom of the picked bag upon the stationary suction face 34, and the downward movement of the suction member being desirably used to turn the suction valve into the space beneath the stationary suction plate.

After the lower pair of wheels enters the depressions 91 at the inward end of the guideway 92, the upper suction member 71 turns upward about the axis of the lower wheels, the folded bag having been placed so that the bottom edge 32 of the upturned side is coincident with this axis. The upper wheel moves along the arc 138, Figure 7, to the full line position, this movement effecting opening of the bag as indicated in Figure 5. The arc 138 is limited by the action of the stop 139 against the side of the movable suction member 71.

The cycle of movements of the movable suction member 71 takes place when the turntable is in its first position of rest to effect picking, presenting, opening and holding of a new bag and again when the same head reaches its last position of rest to effect discharge of the filled and closed bag, and these movements may be accomplished in each case by hand or by suitable mechanism, for example, by means of the pneumatic engines 44 and 45 shown in Figure 4.

In Figures 7 to 10 I have indicated no specific connection between the pneumatic engine and the movable air box 71, intending to indicate that any suitable form of connection might be used or that the box might be moved by hand instead of by any form of engine.

I move the upper suction member 71 preferably by force applied at the axis of the hinge 70 in the pipe connections 66 and 67 between the compartments 49 and 71. In Figure 10a I show a desirable form of hinge connection 70 that includes an annular surface 140 suited for easy and automatic connection and disconnection with the clutches 141 of the pneumatic engines 44 and 45.

The intermediately hinged conduit connections illustrated in Figure 10a between the suction compartments 49 and 68 includes the tubular hub 140, counterpart pipe members 142 and 143 that make spring-pressed wiping connection at 144 with the chamber 68, other counterpart pipe members 145 and 146 making spring-pressed wiping connection at 147 with the compartment 49 at 64 and 65, and a hinge axle member 148 that definitely alines the different tubular portions at the hinge axis.

The hub 140 having its maximum diameter at 149 receives the transversely directed open ends 150 of the pipe members 142 and 143, which in turn engage the open ends 151 of the pipe members 145 and 146.

The members are held together along their pivotal axis by the axle member 148 which has a guiding section at 152 and 153 through the hinge portions of the outer members, made non-circular in order to secure conduit connection between the pipe members.

The axle has threaded end shanks 154 which receive conical washers 155 held to place by nuts 156, desirably using suitable spring washers 157 under the nuts in order to secure resilient clamping together of the members along the hinge axis. 5

It will be seen that the spring unions 144 spring press the transverse ends 150 of the pipes 142 and 143 upon the opposite ends of the hub member to maintain a tight contact against the bevelled ends of the hub member, and that in the same 10 way the spring unions 141 not only press the engaging surfaces to closure at the ports 64 and 65, but also press the transverse ends of the pipes 145 and 146 inwardly into the transverse 15 ends of the pipes 142 and 143, thus holding the members compressed together along the hinge axis.

The tightness of the seal at the hinge axis is desirably increased by the spring washer members 157 under the nuts 156. 20

Details of a desirable form of the pneumatic-engine, 44 or 45, are illustrated in Figures 11 to 15. The same structure is shown generally in Figures 5 and 6. The engines are preferably operated by air pressure or air suction, being illus- 25 trated as operated by air suction.

The engine 44 or 45 has a horizontal pivot support at 160 between the lower ends of downwardly extending forking arms 161 and 162 of a stationary hollow L member 163, suction connection to the engine being effected through the conduit members from a suction compartment 164 inside the body of the turntable. 30

The conduit L member 163 is bolted at 165 to the stationary outer wall of the turntable casting structure, and carries the downwardly depending L branches 161 and 162 at its lower end which support opposite sides of the engine as best seen in Figures 5, 6 and 11 to 13. 35

A piston 166 is adapted to travel back and forth 40 along a cylinder 167, the clutch 141 being carried at the projecting end of the piston rod 168, the clutch member being adapted to receive the hub 140 as the turntable comes to rest, and the desired cycle of movement of the suction box being effected after the turntable comes to rest by a back and forth movement of the piston and through the clutch and hub members 141 and 140. 45

Outwardly enlarged end portions 169 and 170 of the cylinder are provided at horizontally opposite sides with alined lugs 171 and 172 which are bored to receive pipe members 173 and 174 that form a casing for piston valves 175 and 176 mounted upon suitable stems 177 and 178 for controlling the admission of suction to opposite 50 ends of the cylinder.

Ports are provided at 179 and 180 between the interior of the pipe members 173 and 174 and the ends of the cylinder, and also at 181 and 182 from the interior of the pipes 173 and 174 outward along the pivotal axis of the cylinder through head portions 183 and 184 of an inverted saddle member 185 that supports the cylinder by gripping the pipes 173 and 174. 55

The ports 181 and 182 open into the spherical 60 open ends of nipples 186 that are carried by and connect into the lower ends of the suction conduit L connections 161 and 162. Lock nuts 187 retain the threaded nipples in position.

The cylinder is also provided with alined lugs 70 188 which carry a tube 189 into which telescopes a rod 190 mounted upon an inwardly projecting arm 191 of the clutch 141 to maintain the clutch member in unchanged alinement throughout the movements of the piston. 75

The cylinder is thus carried by the inverted saddle 185 at the middle of the tubes 173 and 174 (Figures 12 and 13), the cylinder pivoting in a vertical plane radial of the turntable about the 5 axis of the horizontal suction nipples 186 which maintain continuous suction inside the pipes 173 and 174 intermediate the piston valves thereof. The piston is adapted to travel in either direction according to the setting of the piston valves 175 10 and 176 as determined by the longitudinal setting of the valve stems 177 and 178.

The valve stems 177 and 178 have slot and pin operative connections at 192 and 193 respectively with duplicate rockers 194 and 195.

15 The rockers 194 and 195 have a common pivot support on a pin 196 that is in turn carried between spaced lugs 197 and 198 of a plug 199 in one end of the cylinder.

The rockers 194 and 195 have inwardly extending toes 200 (Figure 15) which are adapted to stop against an outwardly directed surface of the plug 199 when the rockers are in the position shown in Figure 13. In this position suction is admitted into the left end of the cylinder in order 20 to start the piston on its operating cycle,—first to the left from the position of Figure 13, with a subsequent return incident to an automatic reversal of the rockers 194 and 195.

The rockers 194 and 195 respectively carry 30 transversely extending rods 201 and 202 (Figure 14) which are rigidly fastened to the respective rockers and connected at their outer ends by strong springs 203.

The springs 203 pull the pin portions 201 and 35 202 of the rockers toward one another, which tends to move the rockers one way or the other according to whether the pins are both to the left or both to the right of the rocker pivot 196. Therefore the rockers are pulled to the left when 40 they are in the position of Figure 13 and to the right when they are in the position of Figure 15.

Each of the rockers 194 and 195 gives loose pivot support to one end of a bow-shaped mount 45 204 of an outwardly presented roller 205 for use in reversing the rockers from the position of Figure 15 to that of Figure 13.

The mount 204 comprises duplicate bow-shaped pieces loosely pivoted at one end on the pin 201 and at the other end on the pin 202 slotted about 50 one or both of the pins, as at 206 to permit the requisite arcuate movement of the rockers.

The roller 205 is carried at the middle of the bow on a suitable pin 207. It is presented in the path of wedge members 208 (Figures 5 and 11) 55 that are mounted on the turntable in position to successively engage and inwardly deflect the roller from the position indicated in Figure 15 to that shown in Figure 13 each time the table comes to rest.

60 It will be understood that the cylinder does not change its angular position about the turntable.

The wedge members 208 are mounted on the turntable, one for each head, in position to engage and reverse the angular position of the rockers 194 and 195 from the position shown in Figure 15 to the position shown in Figure 13 as the table comes to rest after each periodic advancement. This occurs successively for each head as the head reaches its discharge position 70 5 (Figure 4) and again when it comes to rest in its receiving position, position 1 of Figure 4.

The result of reversing the valve positions from that shown in Figure 15 to that shown in Figure 13 is to make the piston move to the left from 75 its position in Figure 13 until an accompanying

arcuate movement of the cylinder about its pivot 160 effects a reversal of the rockers 194 and 195 as the suction box 71 reaches picking or discharge position, thereby returning the piston to its original position, that of Figure 15.

As the piston moves to the left, extending its rod and moving the suction member 71 to the left, the cylinder has an accompanying arcuate movement about its pivotal axis as indicated in Figures 16 to 21 respectively, a stationary wedge 10 209 (Figure 5) entering the space between the edges 210 and 211 (Figures 13 and 15) of the rockers 194 and 195, forcing the rockers outward until there is a snap reversal due to the springs 203 when these pass outward beyond the 15 rocker pivot 196.

The wedge 209 may be adjusted by experiment so that it effects a reversal of the valves when the travelling suction member has reached the outer end of its stroke.

In Figures 7 and 8 I show straight pipe sections 212 between the hinges 70 and the suction compartment 68.

Ordinarily the pipes 212 will be straight or bent, according to the character of connection 25 made with the outer end of the operating member. With the clutch connection shown in Figures 5, 6, 10a and 11 it is preferable to provide a bend in the pipes 212 at 213, adjacent the hinge connection, in order to provide easy clearance 30 between these pipes and the clutches 141.

Each clutch 141 is angularly stationary with respect to the turntable while each head carries a transverse hub member 140 at the hinge 70, to be received in and clamped by the clutches 141 35 on the piston rods of the cylinders 44 and 45.

The spring clutch members 141 are placed in register with the common orbit of the hub members 140 so that these members travel successively into the clutches 141, one of the hub members having operative connection with each clutch during each rest period of the table, to move on out of the clutch at the next forward movement of the table.

In Figures 16 to 21 I show the relative positions 45 of the cylinder 44, of the movable suction member 71 and of the intermediate connections at the different stages of the operating cycle, showing in dot-and-dash lines on each figure the determinant paths of movement of different 50 parts of the mechanism.

The lines $abcdfa$, $a_1b_1c_1d_1e_1f_1a_1$, $a_2b_2c_2d_2e_2f_2a_2$, $a_3b_3c_3d_3e_3f_3a_3$ respectively indicate the paths of movement of the axis of the upper wheels 118, of the axis of the lower wheels 90, of the axis of 55 the hub 140, and (to indicate the arcuate movement of the cylinder) of a point on the rearwardly extended end of the piston rod.

Corresponding letters on the different lines indicate corresponding points of the different parts 60 at the same stages of the cycle, the stages being indicated respectively by the letters a , b , c , d , e , and f .

Figure 16 indicates the movable parts in the a position, the movable suction member being in 65 the position that it occupies after the bag has been picked, presented to the stationary suction plate and opened, and in which the bag as the head progresses around its orbit remains open as indicated at 215 while it is filled and jarred, 70 being then closed as indicated at 216. The shift to the position of Figure 17 takes place when the turntable carries the head into position 5 (Figure 4) preparatory to discharge.

As the head is brought into the discharge posi- 75

tion the suction member is raised out of the depression 91 by the engagement between the valve knob 101 and the stationary wedge 102, Figure 4, in order to shut off the suction from the stationary plate and to admit air beneath this plate.

The parts are then in the *b* position, as indicated in Figure 17, ready for discharge, the suction in the cylinder 45 having just been reversed by an engagement between one of the wedge members 208 with the roller 205 (Figures 5, 13 and 15).

In Figure 18 the parts have progressed to the *c* position, the movable suction box 71 having been moved by the advancing piston horizontally to the left with the suction face 31 of the box vertical until the lower wheel comes to rest at the point *c*, the moving upper wheel being shown at the point *c* about to travel along the arc *cd*.

In Figure 19 continued advancement of the piston has moved the upper wheels of the movable suction member along the arc *cd* until they have come momentarily to rest at *d* with the suction face horizontally downward in discharge position.

The final downward movement of the box 71 has released the filled bag from the plate 31 by an engagement between the valve operating member 114 and a stationary wedge 117, Figures 9 and 10, and the accompanying arcuate movement of the cylinder 45 has by means of the co-operating wedge 209 (Figure 5) and rockers 194 and 195 (Figures 13 and 15) reversed the suction in the cylinder.

The bag is indicated in dot as still adjacent the suction plate, but is free from the suction plate and falling away for delivery to any desired receptacle through a suitable chute not shown.

Figure 20 shows the parts in the position *e*, the piston having retracted the parts from the positions shown in Figure 19. The suction face 31 has during retraction remained horizontal, the lower wheel 90 having come to a position at the right end of its path preparatory to moving down into the depression 91, while the upper wheels are shown about to move correspondingly downward along *ef*.

Figure 21 shows the positions after the movable suction plate has moved downward, this small downward movement being used to turn 50 suction into the stationary suction plate.

The next position will correspond to that shown in Figure 16 except that there will be no bag present, the cycle of Figures 16 to 21 repeating when the turntable comes to position *f*, at 55 which the mechanism picks up, presents and opens another bag.

It will be understood that the point *o* represents the pivotal axis of the cylinder.

The engines 44 and 45 at positions *l* and *5* may 60 be exactly alike and for this reason it is sufficient to show part of the cycle on one of these cylinders and the remainder on the other cylinder.

In the previous figures I have indicated that the movable and fixed suction plates may have 65 perforated metallic surfaces to come in contact with the bags.

I regard the form shown in the early figures as 70 diagrammatic rather than particularly desirable for the several reasons that the metal contacts with the bag permit excessive leakage; that the suction applied at the center of the plate (i. e., to the center of the bag) is not desirable on account of leakage through the bottom of the bag 75 and because the openings nearest the axis about

which the movable suction plate swings act on so short a leverage as not to be fully effective.

For these several reasons in practical or commercial operation I plan to use resilient sealing edges for contact with the bag to prevent excessive leakage of air between the bags and the suction plates, so as not to require the pumping of excessive leakage air to maintain the vacuum; to avoid application of the vacuum at the middle of the bag and to apply the vacuum where its hold will have the greatest leverage with respect to the axis about which the movable vacuum/plate turns. I find it preferable in practice to use resilient sealing edges to prevent excessive leakage of air between the bags and the suction plates.

In the form of Figures 22 to 25, a sealing edge between the bag and the plate greatly reduces the air leakage, so that the vacuum need not be so high as in the form of Figures 1 to 10.

The movable suction plate 25, seen in Figures 22 and 23, consists of a suction face 214 having perforations 215 opening into the suction box, and an edge plate 216 held by screws 217. A resilient sealing sheet 218, preferably of rubber or similar material, is held between the suction face 214 and the edge plate 216 in a depression 219 extending around the suction plate. The sealing sheet is upwardly pressed at 220 by the shoulders 221 extending around the suction plate near to the inner edge of the sheet.

Thus it will be seen that a bag placed in contact with the movable suction member will be drawn in against the suction face 214 at the center, and upwardly bent at 220 by the resilient sheet. The sheet will itself move inwardly to a variant extent depending upon the pressure applied to it, and will therefore compensate for any irregularities in the surface of the bag, as for example the lumps produced by seams and folds.

The fixed suction member 26 is shown in Figures 24 and 25. The suction face 222 is united to the guard 223, covering most of the face, by the screws 224. Between the face and the resilient sealing guard a sheet 225 preferably of rubber or similar material, is held firmly, so that it will curl at 226 due to the effect of the pressure. The curled inner edges 226 of the sheet lie directly above the perforations 227 in the suction face.

It will be noted that the resilient seal and the 50 perforations in the fixed suction plate are intended to register with only a small portion of the bottom of the bag at a position considerably removed from the axis of opening of the bag, so that the lever arm by which the bottom is held will be a maximum. The suction is not desirably applied to the entire bottom surface of the bag because of its extreme irregularity and because frequently the gluing and folding are sufficiently imperfect so that openings exist from the bottom 60 into the interior of the bag. Where this is the case, suction from the stationary suction face will be admitted to the interior and will tend to oppose the action of the movable suction plate in opening the bag.

It would of course be possible to place the perforations at any point desired over the suction plate, but I prefer to place them at that point on the plate near to the edge of the bag farthest removed from the axis of turning about which the bag is opened. Separate suction openings might of course be placed at other points on the suction face.

The resilient edge 226 of the sheet will tend to compensate for the irregularities of the bottom 75

of the bag, effecting a much more perfect suction seal than would be possible with a metallic suction face only.

In Figure 24 the nob 139' is extended straight out from the suction plate, instead of at an angle as is the nob 139 (Figure 8). This is desirable in some machines.

In view of my invention and disclosure variations and modifications to meet individual whims or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. The method of opening a bag for filling purposes, which consists in engaging the bag by the side and end and in moving the side angularly with respect to the end to open the bag.
2. The method of opening a bag for filling purposes, which consists in engaging the bag by the side and end to open it, in holding it by the side face while it is being filled and in discharging it by release of the hold upon the side face.
3. The method of opening a bag and holding it for filling, which consists in applying suction to the bottom and one side of the bag respectively while the bag is closed and in opening the bag by relatively angularly moving the bottom and side of the bag while maintaining the suction upon them.
4. The method of opening a bag and holding it for filling, which consists in applying suction to the bottom and one side of the bag respectively while the bag is closed, in opening the bag by relatively angularly moving the bottom and side of the bag while maintaining the suction upon them and holding the bag by the suction while it is being filled.
5. The method of opening a bag and holding it for filling, which consists in applying suction to the bottom and one side of the bag by relatively angularly moving the bottom and side of the bag while maintaining the suction upon them, holding the bag by the suction while it is being filled, moving it to the point of discharge while retaining suction support of the bag and discharging the bag by releasing the suction.
6. In the art of bagging, the method of opening a folded paper bag which consists in angularly pulling one side of the bag with respect to the bottom by means of suctions applied simultaneously to the bottom and side.
7. In the art of bagging, the method of using a suction plate to open a folded bag, which consists in holding the bottom of the bag, in applying the plate to the side thereof and in angularly moving the plate about an axis substantially coincident with a common edge of the side and bottom.
8. In the art of bagging, the method of using a pair of relatively movable suction plates to open a folded bag which consists in applying one suction plate to the side of a bag and the other suction plate to the bottom thereof and in angularly moving one of the plates with respect to the other about an axis substantially coincident with a bottom edge of the bag.
9. In the art of bagging, the method of using relatively movable suction faces to pick, present, open and hold a bag for operations incident to filling and closing which consists in applying one of the faces to one side of a folded bag,

moving the face to present the bag so that the bottom thereof is applied to the other face, in angularly moving the one face with respect to the other to open the bag, and in using the two faces in the open position to hold the bag for the filling and closing operations.

10. In the art of bagging, the method of using suction plates for the holding of a paper bag open for filling which consists in applying one plate to the side of the bag and the other plate to the bottom thereof and in positioning and holding the plates for maintaining the bag open.

11. In the art of bagging, the method of using a suction plate which consists in holding the plate against a side of the open bag for bag filling and closing operations, and subsequent to closing, in moving the suction plate to transfer the bag from filling to discharge position and in releasing the suction to drop the bag to discharge.

12. In the art of bagging, the method of using a movable suction plate which consists in moving the plate through a cycle of movement to pick, present and open a bag, in holding it by the plate suction for filling and closing and in repeating the first cycle of movement to discharge the bag, releasing the plate suction at the time of discharge.

13. In the art of bagging, the method of using a suction plate which consists in successively reciprocating the plate, constraining it to present its suction face substantially vertical at one end of its path of movement and horizontally downward at the other end thereof, in using the face to pick, present and open a folded bag during one cycle, to hold the bag for filling and closing operations throughout a period intermediate the cycles and to discharge the filled and closed bag in the next cycle.

14. In bagging mechanism, a pair of relatively movable suction faces, means for applying one of the faces to one side of a bag and for moving the face to present the bag so that the bottom thereof is applied to the other suction face and means for angularly moving the faces, one with respect to the other.

15. In mechanism for opening a folded bag, means for holding the bottom of the bag, a suction plate and means for applying the plate to a side of the bag and then to move it angularly about an axis substantially coincident with the common edge of the side and bottom of the bag.

16. In mechanism for opening a folded bag, two suction plates, means for applying one plate to one side of the bag and the other plate to the bottom thereof and for angularly moving one plate with respect to the other about an axis substantially coincident with the bottom edge of the bag to open the bag.

17. In mechanism for bagging, a suction plate for continuously holding one side of a bag throughout picking, presenting, filling and closure of the bag, means for moving the plate to effect picking, a second suction plate, means for moving the first plate to present the bottom of the bag to the second suction plate, means for angularly moving the first plate with respect to the second to open the bag and for maintaining the first plate in position adapting the cooperating actions of the two plates to hold the bag open, means for releasing the suction in the second suction plate after the bag has been filled and closed and for effecting discharge of the filled and closed bag by moving the first mem-

ber so that its suction surface and depending bag are above the point of discharge and for dropping the bag to discharge by releasing the suction in the first plate.

5 18. In bagging mechanism, a pair of cooperating suction plates one movable and the other stationary, means for applying the movable plate to one side of a folded bag, for moving the plate to apply the bottom of the bag to the stationary 10 plate and while the plates are respectively holding one side and the bottom of the bag for turning the movable plate with respect to the stationary plate in order to open the bag.

15 19. In bagging mechanism, a pair of cooperating suction plates, one movable and the other stationary, means for applying the movable plate to one side of a folded bag, for moving the plate to apply the bottom of the bag to the stationary 20 plate for using the movement of the movable plate as it brings the bag to the stationary plate to apply suction to the stationary plate, and while the plates are respectively holding one side and the bottom of the bag for turning the movable plate with respect to the stationary plate 25 in order to open the bag.

30 20. In bagging mechanism, a pair of cooperating suction plates, one movable and the other stationary, and means for moving and applying the movable plate to one side of a folded bag for using the movement of the movable plate to the bag to turn suction into the movable plate in order to effect picking, and for moving the plate after picking to apply the bottom of the bag to the stationary plate.

35 21. In bagging mechanism, a suction plate for picking, presenting and opening a horizontal folded bag, a guide and cooperating plate moving means giving the plate a movement, comprising an outward movement with the suction surface of the plate turning arcuately downward toward the end of the outward movement and a retraction movement including an earlier portion substantially rectilinear and a later portion during which the suction plate turns arcuately 45 upward.

50 22. In bagging mechanism, a stationary suction chamber having an upwardly directed suction face and spaced ports respectively to a source of suction and to atmosphere, a valve member having surfaces and a range of movement adapting it to close one port when the valve is in one position and the other port when the valve is in another position, each port being open while the other is closed, a movable suction plate 55 adapted to pick a folded bag and to present the bottom thereof to the holding surface of the stationary suction chamber for subsequent holding during opening, filling and closing of the bag, mechanism for positioning the valve for suction in the chamber when the movable suction plate is presenting the bag bottom to the stationary suction face and to reverse the position of the valve subsequent to the closing of the bag in order to permit easy discharge of the bag.

60 23. In bagging mechanism, a stationary suction chamber having an upwardly directed suction face and spaced ports respectively to a source of suction and to atmosphere, a valve member having surfaces and a range of movement adapting it to close one port when the valve is in one position and the other port when the valve is in another position, each port being open when the other is closed, a snap lever operatively connected to the valve, on dead center at an inter- 65

mediate position of the valve, and pressing the valve to closure at either port, a movable suction plate adapted to pick a folded bag and to present the bottom thereof to the holding surface of the stationary suction face for subsequent holding during opening, filling and closing of the bag, mechanism for positioning the valve for suction in the chamber when the second member is presenting the bag bottom to the stationary suction face and to reverse the position of the valve subsequent to the closing of the bag in order to permit easy discharge of the bag. 70

24. In bagging mechanism, a stationary suction chamber having an upwardly directed suction face and spaced ports respectively to a source of suction and to atmosphere, a valve member having surfaces and a range of movement adapting it to close one port when the valve is in one position and the other port when the valve is in another position, each port being open when the other is closed, a movable suction plate adapted to pick a folded bag and to present the bottom thereof to the holding surface of the stationary suction box for subsequent holding during opening, filling and closing of the bag, mechanism adapting the movement of the second suction member to position the valve for suction inside the first chamber and other mechanism to reverse the position of the valve subsequent to the closing of the bag in order to permit easy discharge of the bag. 75

25. In bagging mechanism, a turntable, heads spaced around the table each including movable and stationary suction compartments, the stationary compartment having a suction surface directed upwardly and ports respectively to a source of suction and to atmosphere, a valve member adapted to close either port leaving the other open and provided with an extension, means for moving the upper suction member to pick a folded bag during a position of rest of the turntable and to present the bag with its bottom against the upwardly directed surface of the stationary compartment, means for setting the valve for suction in the stationary compartment when the bottom of the bag is presented thereto, for moving the movable plate upwardly about an axis substantially coincident with the common edge of the bottom and side of the bag in order to open the bag and an operating member for reversing the valve as the turntable brings the head into a subsequent position of rest, the discharge position thereof, releasing the suction hold on the bottom of the bag in order to permit easy discharge of the bag. 80

26. In bagging mechanism, a turntable, heads spaced around the table each including a movable and a stationary suction compartment, the stationary compartment having a suction surface directed upwardly and ports spaced radially of the turntable and opening respectively to a source of suction and to atmosphere, a valve member adapted to close either port leaving the other open and provided with a radial extension, means for moving the upper suction member to pick a folded bag during a position of rest of the turntable and to present the bag with its bottom against the upwardly directed surface of the stationary compartment, means for setting the valve for suction in the stationary compartment when the bottom of the bag is presented thereto, for moving the movable plate about an axis substantially coincident with the common edge of the bottom and side of the bag in order 85

75

to open the bag and an operating member engaging and inwardly deflecting the extension to reverse the valve as the turntable brings the head into a subsequent position of rest, the discharge position thereof, releasing the suction hold on the bottom of the bag in order to permit easy discharge of the bag.

27. In bagging mechanism, a stationary suction chamber having an upwardly directed suction face and spaced ports respectively to a source of suction and to atmosphere, a valve member having surfaces and a range of movement adapting it to close one port when the valve is in one position and the other port when the valve is in another position, each port being open when the other is closed, a valve stem, longitudinally spaced shoulders thereon, outer and inner sleeves on the stem intermediate the shoulders, the shoulders limiting the outward and inward movements of the sleeves along the stem, links adapting the movement of the upper suction plate to presenting position to move the outer sleeve outward beyond its mid position, other links pivotally connected to the outer sleeve at top and bottom thereof at points respectively above and below the stem, the said other levers vertically diverging toward their other ends, laterally extending pins in the said other ends, vertical guideways for the pins, a spring stretched between the pins, adapting the outer sleeve to press inwardly or outwardly according as it is inwardly or outwardly from the vertically guided pins, a movable suction plate adapted to pick a folded bag and to present the bottom thereof to the holding surface of the stationary suction box for subsequent holding during opening, filling and closing of the bag, means for moving the inner sleeve outward when the movable plate moves into presenting position and other means for pressing the stem inward when the head moves into discharge position in order to release the hold upon the bottom of the bag.

28. In bagging mechanism, a movable suction chamber having a suction surface for holding a bag in picking, presenting, opening, holding and discharging operations and having spaced ports respectively to a source of suction and to atmosphere, a valve member adapted to close either port while the other is open, laterally spaced valve operating members each being in while the other is out, an inward deflection of the outward member effecting a reversal of the valve opening one port and closing the other, and means to engage and inwardly deflect one of the operating members preparatory to picking to secure suction in the chamber at picking.

29. In bagging mechanism, a movable suction chamber having a suction surface for holding a bag in picking, presenting, opening, holding and discharging operations and having spaced ports respectively to a source of suction and to atmosphere, a valve member adapted to close either port while the other is open, laterally spaced valve operating members each being in while the other is out, an inward deflection of the outward member effecting a reversal of the valve opening one port and closing the other, and means to engage and inwardly deflect one of the operating members preparatory to discharge to release suction in the chamber at discharging.

30. In bagging mechanism, a movable suction chamber having a suction surface for holding a bag in picking, presenting, opening, holding and

discharging operations and having spaced ports respectively to a source of suction and to atmosphere, a valve member adapted to close either port while the other is open, laterally spaced valve operating members each being in while the other is out, an inward deflection of the outward member effecting a reversal of the valve opening one port and closing the other, a wedge in position to engage and inwardly deflect one of the operating members preparatory to picking to secure suction in the chamber at picking and a second wedge adapted to engage and inwardly deflect the other member as the chamber moves into discharge position.

31. In bagging mechanism, a movable suction chamber having a suction surface for holding a bag in picking, presenting, opening, holding and discharging operations and having spaced ports respectively to a source of suction and to atmosphere, a valve member adapted to close either port when the other is open, snap mechanism spring-pressing the valve to closure at either port, laterally spaced operating members each being in while the other is out and an inward deflection of the outward member effecting a reversal of the valve, opening one port and closing the other, means engaging and inwardly deflecting one of the operating members preparatory to picking to secure suction in the chamber at picking and means engaging and inwardly deflecting the other member as the chamber moves into discharge position.

32. In bagging mechanism, a movable suction chamber having a suction surface for holding a bag in picking, presenting, opening, holding and discharging operations and having spaced ports respectively to a source of suction and to atmosphere, a valve member adapted to close either port while the other is open and snap mechanism spring pressing the valve to closure at either port, including parallel operation members, a rocker pivoted intermediate the members and having loose operating connections at its opposite ends with the respective members, an operative connection between one of the members and the valve stem and a spring fastened to the rocker at one end and anchored to a stationary structure at the other adapting it to be in dead center at an intermediate position of the rocker so as to spring press the rocker in either direction in order to effect spring closure of the valve upon either one of its ports that respectively connect the chamber to suction or to atmosphere.

33. In bagging mechanism, a turntable, circumferentially spaced heads thereon, each carrying a movable suction chamber having a suction surface for holding a bag in picking, presenting, opening, holding and discharging operations and having spaced ports respectively to a source of pressure and to atmosphere, a valve member adapted to close either port while the other is open, laterally spaced operating members each being in while the other is out and an inward deflection of the outward member effecting a reversal of the valve, opening one port and closing the other, a wedge in position to engage and inwardly deflect one of the operating members preparatory to picking to secure suction in the chamber at picking and a second wedge adapted to engage and inwardly deflect the other member as the chamber moves into discharge position, one wedge being adapted to move the valves of the successive chambers to secure suction in the chambers while the heads are successively in one

position of rest of the table, that at which picking is effected and the other wedge reversing the valves successively to release suction when the heads are successively at another position of table rest, the bag discharge position thereof.

34. A stationary suction plate, a movable suction box having inward and outward positions at opposite ends of a range of movement, an inner position at which its suction face is substantially perpendicular to the suction face of the stationary plate and an outer position at which its suction face is directed downwardly, in combination with means for moving the box periodically along a cycle including an outward movement having a downward arcuate portion at the end thereof and an inward movement ending with a substantially ninety degree arcuately upward movement.

35. A stationary suction plate, a movable suction box having inward and outward positions at opposite ends of a range of movement, an inner position at which its suction face is substantially perpendicular to the suction face of the stationary plate and an outer position at which its suction face is directed downwardly, in combination with spaced pairs of supporting wheels on the movable box, a generally horizontal runway supporting the lower wheels, horizontal upper rails supporting the upper wheels along an early portion of the return movement thereof and the rearward ends of the upper rails being adapted to lift upwardly to pass and latch under the upper wheels as they move upwardly from the lower rail, thus insuring that on the next outward stroke of the compartment the upper wheels will again ride outward on the upper rail.

36. A stationary suction compartment having an upwardly directed face, a movable suction compartment having a range of movement and presenting a suction face at one end of its range of movement in position to hold the side of an open bag while a suction face of the stationary compartment is holding the bottom of the bag and at the other end of its range of movement adapted to present its suction face downward to an upturned side of a folded bag to effect picking in combination with upper and lower pairs of wheels on the movable compartment, a generally rectilinear guideway for the lower wheels, upper and lower pairs of rails for the upper wheels, the upper rails and lower guideway supporting the pairs of wheels so that the suction face is in an angularly raised position throughout an early portion of each forward stroke and permits an arcuate downward movement of the face about the axis of the lower wheels to picking position at a later portion of the stroke, and gate means adapting the upper wheels to pass arcuately downward from the upper to the lower pairs of rails and latching above the wheels when they reach the lower rails thereby insuring that during the return stroke of the box the upper wheels travel along the lower rails in order to present the bottom of the picked bag to the stationary plate.

37. In mechanism for bagging, a stationary suction plate, a movable suction plate having inward and outward positions at opposite ends of a range of movement, an inward position at which its suction face is directed substantially perpendicular to the suction face of the stationary plate and an outer position at which its suction face is directed downwardly in combination with a cooperating guide and motor adapted to periodically reciprocate the movable plate throughout its back and forth movements in a way such that each outward movement ends with

an arcuate turning of the suction face downward and each inward movement ends with an arcuate raising of the suction face from a position at which it is horizontally downward to a position at which it is substantially vertical.

38. In mechanism for holding bags, a stationary suction plate, a movable suction plate, means for engaging a bag by the movable suction plate, means for shifting the position of the movable suction plate until the bottom of the bag comes into engagement with the stationary suction plate and means for tilting the movable suction plate in engagement with the side of the bag to open the bag while the bottom is held by the stationary suction plate.

39. In mechanism for opening and holding bags, a movable suction plate adapted to occupy a horizontal position in engagement with the side of a folded bag, means for shifting the movable suction plate and the bag engaged by it, means for lowering the movable suction plate, a fixed suction plate engaged by the bottom of the bag when the movable suction plate is lowered and means for tilting the movable suction plate to open the bag by swinging the side wall of the bag while the bottom of the bag is held.

40. A pair of relatively movable suction plates, one a side-holding plate and the other a bottom-holding plate, the plates being adapted to lie in substantially parallel position with the side engaging plate holding the side of the bag, means for moving one of the plates until the bottom of the bag and the bottom-holding suction plate engage and means for tilting one of the plates until the side of the bag is moved to a position perpendicular to the bottom of the bag to open the bag.

41. A pair of relatively movable suction plates initially parallel, means for applying one of the plates to the side of a bag and applying vacuum thereto, means for applying the other plate to the bottom of the bag and connecting with the vacuum and shifting mechanism for one of the plates moving it angularly with respect to the other plate to open the bag.

42. In bag opening and holding mechanism, a pair of vacuum plates initially having their faces parallel, mechanism for connecting the plates respectively with a vacuum, guides for both plates providing for shifting the plates together and turning mechanism for one of the plates whereby it is moved angularly with respect to the other to open the bag.

43. A pair of vacuum plates having their faces initially parallel, guides for relatively shifting the plates substantially in their initial planes, means for relatively angularly shifting the plates, means for applying a vacuum to one of the plates, mechanism set in motion by the second shift for applying vacuum to the other of the plates and turning mechanism for one of the plates to open them angularly one with respect to the other in order to open the bag.

44. A pair of vacuum plates having their faces initially paralleled, guides for shifting one plate in its initial plane and for engaging the plate with a bag, and means for opening the plates angularly, one with respect to the other to open the bag.

45. A turnable having a suction compartment and hollow arms spaced around the table having conduit connection with the compartment, and stationary and movable suction boxes upon each arm having conduit connection with the hollow of the arm, said connection for the movable box

including pipes adapting the movable box to a range of movement for effecting picking, presenting, opening and holding of a folded bag.

46. A turntable, hollow suction arms spaced therearound, and two relatively movable suction plates on each arm in flexible conduit connection with the hollow thereof and adapted to pick, present, open and hold a bag.

47. A turn table, hollow suction arms fixed thereabout, a pair of relatively movable suction plates on each arm, each pair being adapted to pick, present and open a folded bag when at one position of the table, a mount for each mechanism, an upwardly and downwardly resilient connection between the mount and the table, and a downwardly presented projection from the mount to receive vibration for it through the mount to the mechanism in order to jar a filled bag without materially vibrating the table.

48. A turntable, a plurality of arms spaced therearound, each arm having a vertical bore, picking and holding mechanism for each arm, a mount therefore having a shank surrounded by the bore threaded below the bore, a nut on the threaded portion below the bore and rubber insulation above and below the bore separating the mount from the arm and adapting the mechanism to receive vibration for jarring the filled bag without transmitting it materially to the arm.

49. A turntable, a plurality of hollow arms spaced therearound, each arm having a vertical bore at its outer end through the hollow arm and presenting substantially horizontal surfaces above and below the bore, suction picking and holding mechanism for each arm, a mount for the mechanism, a hollow shank thereon surrounded by a bore and having a threaded shank and nut below the bore and ports into the interior thereof from the hollow of the arm and rubber washers compressed above and below the bore vertically insulating the mount from the threaded portion of the shank thereby adapting the mount to receive vibration for transmission to the mechanism in order to jar a filled bag.

50. A turntable, suction heads spaced therearound, a movable suction box on each head, a guide for each box providing a cycle of movement along which the box is adapted to pick, present and open a folded bag at a rest position of the heads, a rocker pivotally mounted on the head and having a link connection with the box adapting angular reciprocation of the rocker to move the box throughout its cycle, a clutch hold mounted on the rocker and comprising an axially operating crank pin therefor, the pin being horizontal and directed inwardly axially tangential to the circular movement of the table, an open clutch adapted to partially surround the clutch hold, a rod mounting the clutch, normally presenting the clutch in transverse registry with the common path of the clutch holds and in engagement with one of the holds after the other during successive rest periods of the table, and means for longitudinally and angularly reciprocating the rod during each rest period in order to move the

box at the clutch throughout its cycle of movement.

51. A turntable, suction heads spaced therearound, two relatively movable suction boxes on each head in suction connection therewith, a rocker adapted to move the box along a cycle of movement during which one box is adapted to pick, present and open a folded bag in conjunction with another box, a piston rod adapted to longitudinal and angular reciprocation and a clutch connection between the piston rod and movable suction box adapted to automatically connect with the rockers of the successive heads as these come successively to rest at the rod and automatically disconnect from the rocker at the rod as the head passes onward from the rod.

52. A turntable, movable members spaced therearound, each adapted to pick a folded bag at one rest position of the member and to discharge the filled bag at another rest position thereof, two pneumatic engines having stationary supports inwardly from the members, one at the picking position and one at the discharge position, clutch means on each engine adapted to automatically connect and disconnect with the movable members, one clutch connecting with the movable member at the picking position while the other connects with the member at the discharge position, each engine during the rest period of the table being adapted to reciprocate in order to move the said member with which it is then connected through its cycle of movement.

53. A first vacuum plate and a second vacuum plate, the said plates having their faces in bag pick up and bag receiving positions respectively, substantially parallel, guides for relatively shifting the plates toward one another to bring a picked up bag to the second plate, means effective after the first shifting for angularly shifting one plate with respect to the other, means effective prior to the first shifting for applying a vacuum to the first plate, and means effective subsequent to the first shifting for applying a vacuum to the second plate.

54. A first vacuum plate and a second vacuum plate, the said plates being relatively movable and adapted to engage different portions of a bag and, when respectively in their pick-up and receiving positions, having their faces substantially parallel, means for relatively shifting the plates for engaging the second plate with a bag already engaged by the first plate and other means for opening the plates angularly, one with respect to the other, to open the bag.

55. A turntable, hollow suction arms spaced thereabout, a pair of relatively movable suction plates on each arm, each pair being adapted to pick, present and open a folded bag when at one position of the table, a mount for each mechanism, an upwardly and downwardly resilient connection between the mount and the table, and a downwardly presented projection from the mount to receive vibration for transmission through the mount to the mechanism in order to jar a filled bag without materially vibrating the table.

HAROLD G. EYNON.
